PULL SWITCH FOR MINE SHAFT SIGNAL SYSTEMS

Filed June 18, 1948

FIG. 1.

FIG. 4.

UNITED STATES PATENT OFFICE

2,586,722

PULL SWITCH FOR MINE SHAFT SIGNAL SYSTEMS

Richmond L. Rutherford, Superior, Ariz.

Application June 18, 1948, Serial No. 33,739

3 Claims. (Cl. 250—36)

1

My invention is related to mine shaft signal systems as set forth in U. S. Letters Patent No. 2,248,825 granted to me July 8, 1941, in which signals are dispatched from an elevator cage, or skip, in a mine shaft by means of an oscillatory circuit, said signals being reproduced in a radio frequency receiver located at the mouth of the shaft. The radio frequency sending apparatus embodies the use of one or more thermionic vacuum tubes in a feed back circuit to which current is supplied by a battery carried on the elevator cage and by reason of the space available for accommodation of the apparatus it is desirable to make it compact and operate it from a small battery. Inasmuch as the energizing of the circuit is only required at the time when it is desired to transmit a signal I have found in practice that it is desired to transmit a signal I have found in practice that it is preferable to maintain it inoperative and thus extend the life of the thermionic tube or tubes and also maintain the voltage of the battery.

The object of my present invention is to incorporate in conjunction with the switch employed for interrupting the oscillatory circuit when radio signal waves are to be dispatched, means for first energizing said circuit so that by means of a single instrumentality in the hand of the operator these results may be accomplished seriatim without thought on his part.

Another object of my invention is to conserve the power of the battery used for energizing the oscillatory circuit to obviate the necessity of frequently renewing it as is the case where said circuit is maintained energized continuously by providing a switching means which is so arranged that the battery current is applied automatically when the operator grasps the signal handle preparatory to transmitting a radio signal, there being provided a delayed action between the energizing of the oscillatory circuit and the pulling of the signal cord which occurs independently of any action on the part of the operator.

To these and other ends my invention comprises further improvements and advantages as will be further described in the accompanying specification, the novel features thereof being set forth in the appended claims.

In the drawings:

Figure 1 is a view conventionally illustrating

2

a mine shaft and radio transmitting and receiving apparatus employed in conjunction with the elevator and its hoist.

Figure 2 is a diagrammatic illustration of the signal dispatching apparatus carried on the elevator.

Figure 3 is a similar view of the radio receiving circuit located at the mouth of the shaft which operates in conjunction with the circuit of Fig. 2.

10. Figure 4 is an enlarged view partly in section illustrating a pull switch embodying one form of my invention, the parts thereof being shown in their normal inoperative position, and

Figure 5 is a similar view in detail showing the pull switch in its signal transmitting position.

Figure 6 is a view similar to Figure 4 showing the filaments which are located on the pull cord shaft and operated by means of a Bowden wire from the pull cord handle.

20. Similar reference numerals, in the several figures, indicate similar parts.

Figure 1 shows in cross section a vertical mine shaft 10 in which an elevator cage or skip 11 is lowered and raised by means of a cable 12 carried 25 by the usual hoisting apparatus 13 at the mouth of the shaft.

Carried on the elevator is a radio frequency generator indicated generally by A in Fig. 1 and in the vicinity of the hoist operator's stand in a 30 radio frequency receiver B, having a loud speaker b for reproducing the signals transmitted from the elevator cage, as will be understood by reference to my prior Patent No. 2,248,825.

The oscillator circuit (see Fig. 2) may be of 35 any preferred design and the one employed for illustrative purposes comprises a thermionic vacuum tube comprising the usual cathode 15, grid 16 and plate 17, in circuit with other elements forming the input, output and feed back circuits 40 fed with direct current from a main battery 18.

The input circuit of the tube comprises a fixed inductance 19, one terminal of which is in electrical connection with the elevator cage 11, and thus with cable 12, and also is joined to the grid 45 16. The opposite end of inductance 19 is connected by wire 21 to one end of the secondary winding 22 of an iron core transformer 23 which is connected at its opposite extremity to the tube plate 17. This winding is bridged by a bypass condenser 24.

Low voltage current for heating the cathode of the tube is supplied to one terminal of the cathode 15 from one pole of battery 18 via wire 25 and extending from the other pole of the battery is a connection to the second terminal of the cathode which comprises wires 26 and 27 which lead through the signalling switch to a separate hand operated switch, generally designated by C in Fig. 4, to be later referred to more in detail.

The battery terminals are also connected to the ends of the coil forming the primary winding of transformer 23. In one of these leads indicated by 30 is an adjustable vibrator 31, for controlling the tone of the signal and in the other, indicated by 32 is a switch D the contacts of which are normally open as are also the contacts of switch C.

The apparatus described above takes the place of the more primitive signalling means originally employed in mine shafts consisting of a bell located at the mouth of the shaft and a bell cord or wire suspended in the shaft which an elevator operator would pull to signal the hoist operator. It is because of the general lack of skill of such operators that it has been found in practice desirable to retain a semblance in the operation of this newer apparatus to the original method of transmitting signals that I retain the form of a pull cord due to the fact that all operators are familiar therewith and no special directions or instructions are required in order to teach them the modus operandi of the signal mechanism per se. To this end, therefore, I provide a pull cord 40 suspended from a tubular shaft 41 guided for vertical movement in an aperture in the bottom of the case A containing the oscillator circuit. The shaft is held in a normal retracted position, as shown in Figs. 2, 4 and 5, by a coil spring 42, enclosed in a casing 43 and operating against a collar 44 which engages the outer face of the bottom of case A. The upper, or inner end of shaft 41 has an outwardly flaring rim 45 which when the shaft is pulled downwardly serves to deflect a spring arm 50 associated with switch D for moving the switch plunger 51 to close the oscillator circuit, as shown in Fig. 5.

At the lower end of the pull cord, 40 is an operating handle 55. This is hollow and contains the switch C which has terminals for the cathode wires 26, 27 which are led through the top of the hollow shaft 41 and the tubular pull cord.

I deem it important that whatever means is employed for closing the cathode circuit that the arrangement be such that when the operator grasps the handle 27 that switch C be immediately closed and retained closed during the dispatching of signal impulses. This calls therefore for a special construction of the handle and the provision of a lag or delayed action in the closing of the signal circuit at switch D. The delayed action is accomplished by providing a short travel in the movement of shaft 41 before its flange 45 engages switch spring 50. As an example of one form of construction of handle 27 I have shown it provided on one edge with a sinuous grip portion 60 for engagement by the operator's fingers. Extending longitudinally of this grip portion of the handle is a slot 61 and lying therein is a presser plate 62 which is guided at its ends by slotted flanges 63 guided on pins 64. The plate is normally moved outwardly by the free end 65 of a bow spring the other extremity 66 of which may be attached to switch C and arranged to actuate the switch plunger 67 when the plate 62 is moved inwardly.

In Figure 6 I have shown another relative dis-

position of the two switches, the signal switch being indicated by D' and the cathode circuit switch by C'. In this instance switch C' is mounted rigidly on the inner end of the pull cord shaft 11 and its terminals are closed by a spring arm 10 the upper end of which projects over the open end of said shaft. A Bowden wire 12, extending through the latter and the pull cord, is attached at its upper end to spring 10 and at its lower end to a trigger 13 pivoted on the pull end handle 14 and normally held in an inoperative position by an expansible spring 15. In this arrangement of the parts it will be seen that when the operator grasps the handle 14 and closes the trigger 13 against it that the cathode circuit will be first closed through switch C' to render the oscillator circuit active before he transmits a radio frequency impulse by a downward movement of the pull cord to close the signal transmitting circuit through switch D'.

In the structures described it will be observed that in a single instrumentality I have provided means for conserving the life of both the battery and the thermionic vacuum tube and assuring that an operator observe the necessary sequence in operation in rendering operative two different circuits with a delayed operation of one of them. Moreover, following the act of readying the two circuits the one which must be first closed is maintained closed while the second is opened and closed for signalling purposes and is finally opened upon discontinuing the signals. It will be further noted that the described sequence in operation of the two circuits is accomplished automatically and without the exercise of skill on the part of the operator.

I claim:

1. In mine shaft signalling apparatus embodying a radio frequency oscillator comprising a thermionic vacuum tube having a cathode provided with a heating circuit, associated input and output circuits for generating signal impulses and a source of battery current supply for said circuits, a longitudinally movable spring biased member having an operating handle, a trigger thereon adapted to be operated when the handle is grasped, a switch in the cathode circuit controlled by movement of the trigger and a switch controlling the other circuits for the dispatch of signals arranged to be actuated upon the longitudinal movement of said member against said bias subsequent to the closure of the first mentioned switch.

2. A signal device for mine shafts comprising a radio frequency oscillation generator including a vacuum tube having a cathode, associated input and output circuits for generating signal impulses and a source of battery current supply for said circuits, a cathode heating circuit, a switch connected in said cathode heating circuit, a longitudinally movable spring biased member having an operating handle, said operating handle including a Bowden wire extending through said longitudinal member and adapted to actuate said switch when the handle is grasped, a second switch, said second switch being connected in said output circuit, said longitudinal member upon its longitudinal movement against said bias actuating said second switch into circuit closing position.

3. A signal device for mine shafts comprising a radio frequency oscillation generator including a vacuum tube having a cathode, associated input and output circuits for generating signal impulses and a source of battery current supply for

said circuits, a cathode heating circuit, a switch connected in said cathode heating circuit, a longitudinally movable spring biased member having an operating handle, said operating handle having said switch mounted thereon and a spring biased trigger adapted to actuate the switch when the handle is grasped, a second switch, said second switch being connected in said output circuit, said longitudinal member upon its longitudinal movement against said spring bias actuating said second switch into circuit closing position.
